DESIGN FOR A NECKTIE-RACK OR THE LIKE

Abe R. Brothers, Brooklyn, N. Y.

Application January 15, 1943, Serial No. 109,268

Term of patent 14 years

To all whom it may concern:

Be it known that I, Abe R. Brothers, a citizen of the United States of America, residing at Brooklyn, in the county of Kings and State of New York, have invented a new, original, and ornamental Design for a Necktie Rack or the like, of which the following is a specification, reference being had to the accompanying drawing, forming part thereof.

I claim:

The ornamental design for a necktie rack or the like, substantially as shown.

ABE R. BROTHERS.
